SANITARY INDIVIDUAL TOILET SEAT COVER

Herman Halfin, New York, N. Y.

Application March 25, 1942, Serial No. 436,125

11 Claims. (Cl. 194—26)

This invention relates to new and useful improvements in a vending machine for sanitary individual toilet seat covers.

More specifically, the invention proposes the construction of a vending machine for sanitary individual toilet seat covers characterized by a casing having a discharge slot and a coin controlled manual or electric mechanism arranged in a manner to deliver a toilet seat cover from a continuous strip of toilet seat covers located within the casing.

Still further it is proposed to divide the continuous strip of individual toilet seat covers into a plurality of separable covers by the provision of laterally extended lines of slightly elongated perforations between adjacent seat covers in a manner to permit the endmost seat cover to be separated from the continuous roll when projected through the slot in said casing.

Still further it is proposed to provide certain mechanism operable in connection with certain of said elongated perforations for preventing the extension of more than one toilet seat cover for each coin inserted.

It is further proposed to provide an electrically controlled mechanism for slightly extending the endmost seat cover when a coin is inserted to permit the extended portion to be gripped and pulled for completely extending the said endmost cover.

A further object of the invention proposes the provision of means for freeing the endmost seat cover to be extended through said discharge slot when a coin is inserted into said device.

For further comprehension of this invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a vending machine for sanitary individual toilet seat covers constructed in accordance with this invention.

Fig. 2 is an enlarged side elevational view of a portion of Fig. 1.

Fig. 3 is an enlarged partial vertical sectional view taken on the line 3—3 of Fig. 1.

Fig. 4 is a vertical sectional view taken on the line 4—4 of Fig. 3.

Fig. 5 is a front elevational view of Fig. 1 with the front cover of the machine removed.

Fig. 6 is a vertical sectional view taken on the line 6—6 of Fig. 5.

Fig. 7 is a partial vertical sectional view taken on the line 7—7 of Fig. 5.

Fig. 8 is a perspective view of a portion of the roll of individual toilet seat covers.

Fig. 9 is a perspective view of a vending machine for sanitary individual toilet seat covers constructed in accordance with a modification of this invention.

Fig. 10 is a front elevational view of Fig. 9 with the front wall of the machine removed.

Fig. 11 is an enlarged vertical sectional view taken on the line 11—11 of Fig. 10.

Fig. 12 is a partial vertical sectional view taken on the line 12—12 of Fig. 10.

Fig. 13 is an enlarged detailed view of a portion of Fig. 11, partly in section.

Fig. 14 is a horizontal sectional view taken on the line 14—14 of Fig. 13.

Fig. 15 is a partial vertical sectional view taken on the line 15—15 of Fig. 10.

Fig. 16 is a schematic wiring diagram of the device.

The vending machine for sanitary individual toilet seat covers, according to this invention, includes a casing 80 consisting of a body portion 81 adapted to be mounted upon a wall 82 by means of lugs 83. The lugs 83 are formed with openings through which screws 84 are adapted to be passed to be threaded engaged into the wall 82. The body portion 81 has a removable cover 85 which is provided adjacent its bottom with an elongated horizontal discharge slot 86. A mirror 87 is mounted upon the cover 85 at a point above the slot 86. This mirror 87 is preferably constructed of a piece of sheet metal having a highly polished exposed face. Mounted between the mirror 87 and the discharge slot 86 the face of the cover 85 is provided with a plurality of receiving frames 88 in which printed advertising material 89 is adapted to be mounted.

Adjacent one side of the mirror 87 the front cover 85 has the receiving opening 90 of a coin controlled mechanism 91. Further details of the coin controlled mechanism 91 and the manner in which it is to be used in this invention will be given as this specification proceeds.

Means is provided for releasably retaining the front cover 85 in position upon the body portion 81 of the casing 80. Metallic members 92 are secured upon the bottom side portions of the front cover 85 by means of rivets 93. These metallic members 92 are arranged horizontally and each is provided at its free end with a lug 94 which projects from the bottom edge thereof. The free ends of the metallic members 92 are engageable

with complementary keeper members 95 mounted upon the sides of the body portion 81. The keeper members are in the form of U-shaped brackets mounted upon the body portion by means of rivets 96. These U-shaped brackets 95 form spaces 97 through which the free ends of the metallic members 92 engage to cause their lugs 95 to engage the back edge of the keeper members 95 as shown in Fig. 2.

A lock 98 is provided for securing the top portion of the cover 85 in position and to prevent the disengagement of the metallic members 92 from the spaces 97 except if the lock 98 is released. The lock 98 is characterized by a key cylinder 99 mounted upon the cover 85. A bolt 100 projects from the key cylinder and is engageable with a complementary opening 101 in a keeper 102 mounted upon the top wall of the body portion 81 of the casing 80. The bolt 100 has a projecting lug 103 which is adapted to pass through a complementary cutout 104 extending upwards from the opening 101. When the bolt 100 is turned relative to the keeper 102 and lug 103 will engage behind the keeper 102 and prevent the bolt 100 from being withdrawn from the keeper.

A web of toilet seat covers 105 is wound upon a core 106 frictionally mounted upon a shaft 107. The shaft 107 is rotatively supported in a pair of spaced brackets 108 mounted upon the side walls of the body portion 81 of the casing 80. The web is divided into a continuous line of separable covers 105 by means of laterally extending lines of slightly elongated perforations 109. Each cover has a substantially oval shaped central opening 110.

The endmost seat cover 105 is extended downwards within the casing 80 over an idler roller 111 mounted upon the back wall of the body portion 81. This free end is then projected between a pair of feed rollers 112 and then through the slot 86.

A pin bar 113 is vertically slidably mounted at a position adjacent the bottom of the slot 86. This pin bar 113 is provided at its ends with a plurality of upwardly extending pins 114 which are adapted to project through the remaining portion of the perforations of the endmost seat cover 105. The free top ends of the pins 114 then are extended into complementary openings 115 formed in a bar 116 mounted upon the cover 85 immediately above the top edge of the slot 86.

The mounting of the pin bar 113 to permit vertical movement is accomplished by providing a plurality of pins 117 which extend from the bottom wall of the body portion 81 and which extend through complementary openings 118 formed in the pin bar 113. The pin bar 113 is substantially U-shaped in configuration, and certain of the pins 117 engage the side arms of the pin bar and others engage the intermediate arm. Collars 119 are mounted upon certain of the pins 117 for limiting downward movement of the pin bar 113 to a position in which the pins 117 will be completely disengaged from the openings 115 formed in the bar 116 and in which their top ends will be disposed beneath the bottom edge of the slot 86. Other of the pins 117 have expansion springs 120 wound coaxially thereon for urging the pin bar 113 in a normal position in which the pins 114 engage into the openings 115 in the bar 116. The pin bar 113 is formed of light weight material, and the springs 120 are weak in nature, but exert a sufficient force to raise the pin bar 113 into its operative position.

A rod 121 controlled by the coin controlled mechanism 91 is provided for lowering the pin bar 113 to retract its pins 114 to free the endmost seat cover 105 to be withdrawn through the slot 86. 5 The rod 121 is slidably mounted in brackets 122 and has its bottom end resting upon the top face of the pin bar 113. More specifically, the rod 121 is bifurcated beneath the uppermost bracket 122 and has its free end resting upon the side arms 10 of the pin bar 113.

The coin controlled mechanism 91 is characterized by a container 123 mounted upon the top wall of the body portion 81. The container 123 has an internal chute 124 which continues into 15 the receiving opening 90 which is projected through the front cover 85. A coin (indicated by the dotted lines 125 in Fig. 6) is adapted to be passed into the receiving opening 90 to roll down the chute 124. The free end of the rod 121 is 20 projected upwards into the container 123 to assume a position within the bottom portion of the chute 124. The coin 125 is adapted to pass over and stop upon the free top end of the rod 121 moving it downwards to in turn urge the pin bar 25 113 downwards against the holding action of the expansion springs 120. This downward movement of the pin bar 113 frees the endmost seat cover 105 to be projected through the slot 86.

A rod 126 is projected into the chute 124 and 30 is adapted to be engaged by the leading edge of the coin 125 to hold the coin 125 over the free top end of the rod 121. This will hold the pin bar 113 retracted until such time as the rod 126 is moved to free the coin to roll from the end of the chute permitting the springs 120 to raise the pin bar 113 and rod 121. Further details of the utility of the rod 126 will be given as this specification proceeds.

The feed rollers 112 are mounted upon shafts 40 127 rotatively extended between the side walls of the body portion 81 of the casing. One of the shafts 127 is extended from one side of the body portion 81 and is provided with a Bakelite knob 128 by which the feed rollers may be manually 45 rotated to eject the endmost seat cover 105. The other of the shafts 127 carries a gear 129 which is adapted to be engaged by a pawl 130. This pawl 130 is mounted upon a bracket 131 mounted upon the end of the adjacent side arm of the U-shaped pin bar 113. When the pin bar 113 is in its raised position the pawl 130 engages the teeth of the gear 129 and prevents the rollers 112 from being turned. When the pin bar 113 is urged downwards by the downward movement of the 50 rod 121 the pawl 130 will be retracted from its engaged position with the gear 129, permitting the feed rollers 112 to be rotated through the unobstructed slot 86.

The rod 126 is slidably mounted in a pair of 60 brackets 132 mounted upon one side wall of the body portion 81. The free bottom end of the rod 126 is disposed over the center of the web of toilet seat covers 105 and is provided with a weighted cam 133. This cam 133 rests upon the endmost seat cover and retains the top end of the rod 126 in the path traversed by the coin 125. However, as the endmost seat cover 105 is ejected aligning the central opening 110 of the endmost cover 105 with the bottom end of the rod 126, the weighted cam 133 will drop through the central opening 110 withdrawing the top end of the rod 126, permitting the coin 125 to roll down the chute 124 and free the rod 121 and the pin bar 113. A collar 134 is mounted upon the rod 126 and is adapted to 70 engage one of the brackets 132 to limit down-

ward movement of the rod 126 to a position in which the weighted cam will be partially projected through the central opening 110 and in which the top end of the rod 126 will be completely withdrawn from the path traversed by the coin 125.

As the end of the central opening 110, in the endmost seat cover 105 approaches the weighted cam, the material of the cover 105 adjacent the end of the opening 110 will again raise the rod 126 into its operative position. It will be noted that the pins 114 are mounted only on the ends of the pin bar 113 and when this bar 113 is released, the pins 114 are adapted to bear against the bottom face of the seat cover being withdrawn, preventing the pins 114 from reentering the opening 115 and preventing the pawl 130 from engaging the gear 129. The pins 114 will retain this position until such time as the next complete line of perforations 109 become aligned with the pins 114, and then the pin bar 113 will be urged completely upwards by the springs 120 causing the pins 114 to enter the opening 115 and the pawl 130 to be reengaged with the gear 129 locking the device, but permitting the endmost seat 105 to be torn from the web along the line of perforations 109 now engaged by the pins 114. This operation limits the machine to eject only one seat cover for one coin.

Means is provided for causing the endmost seat cover 105 to be slowly ejected from the slot 86 affording the parts of the machine an ample opportunity to operate as described to limit the device to eject only one seat cover at a time. This means comprises a brake mechanism 135 mounted upon the shaft 107 supporting the roll of toilet seat covers 105. A brake drum 136 is mounted upon the shaft 107 and is encircled by a brake band 137. A lug 138 projects from the band 137 and is mounted upon the side wall of the body portion 81 by means of rivets 139. The ends of the band 137 are directed away from the drum 136 and a screw 140 engages these ends threadedly for drawing the ends of the band 137 together to tightly engage the drum 136 and frictionally retain the shaft 107 from rotating too rapidly.

The operation of this invention is as follows:

A coin is passed into the receiving opening 90 to roll down the chute 124 and be stopped by the top end of the rod 126 over the top end of the rod 121. This will cause the rod 121 to be depressed urging the pin bar 113 downwards disengaging the pins 114 from the openings 115 and the pawl 130 from the gear 129. The knob 128 may now be rotated for rotating the feed rollers 12 to eject the endmost seat cover 105. As the cover is being ejected, the weighted cam will drop into the central opening, moving the rod 126 downwards freeing the coin 125 to discharge from the end of the chute 124 and collect within the container 123. This will free the pin bar 113 to move upwards until its pins 114 engage against the bottom face of the cover 105 being ejected. As the next complete line of perforations 109 approaches the pins 114, the pins will pass through these perforations and enter the openings 115. Simultaneous with this movement of the pins 114, the pawl 130 will reengage the gear 129 and completely lock the machine to prevent the next seat cover from being ejected unless another coin is inserted into the receiving opening.

The ejected seat cover may then be torn from the web along the line of perforations 109 engaged by the pins 114.

The vending machine for sanitary individual

toilet seat covers, according to a modification of this invention shown in Figs. 9 to 16, comprises a casing 10 consisting of a body portion 11 adapted to be mounted on a wall 12 by means of lugs 11a. The body portion 11 has a removable front cover 13. The front cover 13 is provided with a discharge slot 14 for seat covers adjacent the bottom thereof. A mirror 15 is mounted upon the cover 13 at a point above the slot 14. Between the slot 14 and the mirror 15 the front cover 13 is provided with a plurality of receiving frames in which printed advertising material 15a is adapted to be mounted. Adjacent one side of the mirror 15 the front cover 13 has the receiving opening 16 of a coin controlled mechanism 17.

Means is provided for releasably attaching the cover 13 in position across the open front of the body 11. This means comprises angle members 18 mounted upon the top and bottom walls of the body 11. These angle members 18 have one of their arms arranged to extend along the back face of the cover 13 and each of these arms is provided with a central threaded opening 19. Screws 20 are freely engaged through openings formed in the top and bottom portions of the front cover 13 and are threadedly engaged into the openings 19.

A roll of toilet seat covers 21 is fixedly mounted upon a shaft 22 rotatively supported between a pair of spaced brackets 23. The brackets 23 are securely mounted upon the side walls of the body 11 at a point substantially above the discharge slot 14. The roll of seat covers 21 is characterized by a continuous strip of covers 24 which are separated from each other by laterally extended lines of slightly elongated perforations 25' which permit the covers to be separated from the continuous roll by tearing along these lines of perforations 25'.

As shown in Fig. 11 the endmost seat cover 24 extends downwards within the casing 10 and has its free end extended through a pair of superimposed feed rollers 25 to discharge through the slot 14. The feed rollers 25 are fixedly attached 45 to shafts 26 which are rotatively supported between the side walls of the casing 10.

Electrically controlled means is provided for slightly ejecting the free end of the endmost toilet seat cover 24 slightly from the slot 14 permitting 50 the end to be gripped for completely pulling this endmost seat cover through the slot so that it may be separated from the roll of covers 21. This means comprises an electrically controlled solenoid 27 mounted upon the side walls of the casing 10.

The mounting of the solenoid 27 is accomplished by means of brackets 28 extended from the side walls of the casing. The solenoid 27 has a core 28' of magnetic material completely extended therethrough and which connects at its bottom end with a yoke 29 of non-magnetic material. The yoke 29 comprises a horizontal bar 30 attached to the bottom of the core 28' of the solenoid. The ends of the horizontal bar 30 65 continue into downwardly extending side arms 31. One arm 31 is provided on one of its faces with rack teeth 32 which mesh with a gear 33 mounted upon the lowermost shaft 26 supporting the lowermost feed roller 25.

The gear 33 is freely rotatively supported upon the shaft 26 and means is provided for locking the gear to the shaft when turned in one direction for rotating the feed roller 25 when the core of the solenoid is moved downwards. This means 70 comprises a ratchet wheel 34 fixedly mounted

75

upon the shaft 26 adjacent one side of the gear 33. A pawl 35 is mounted upon the adjacent face of the gear 33 and engages the teeth of the ratchet wheel 34. A spring 36 is provided for urging the pawl 35 into continuous engagement with the ratchet wheel 34. When a coin is inserted into the receiving opening 16 of the coin controlled mechanism 17 it closes a circuit, as will be hereinafter described, to energize the solenoid 27 and urge the arms 31 downwards, causing the gear 33 to be rotated. The pawl 35 on the gear 33 will engage the ratchet wheel 34 and rotate the feed rollers 25 to slightly eject the endmost toilet seat cover 24 through the slot 14.

Springs 37 operate between the brackets 28 and the horizontal arm 30 of the yoke 29 for drawing the yoke 29 upwards when the current to the solenoid 27 is cut off. On the return movement of the yoke 29 the gear 33 will be turned in the opposite direction and the pawl 35 will merely idle over the teeth of the ratchet wheel 34, so that the feed rollers will not be turned to draw the projected end of the endmost seat cover into the casing 10.

A pin bar 38 is vertically slidably mounted at a position adjacent the bottom of the slot 14. This pin bar is provided at its ends with a plurality of pins 39 which are adapted to engage the side perforations of the line of perforations 25' for preventing the ejection of more than one toilet seat cover on any one operating cycle of the device. This pin bar 38 is mounted in such a manner that its pins 39 are adapted to engage into complementary openings 49 formed in a bar 41 mounted upon the front cover 13 adjacent the top of the slot 14.

The mounting of the pin bar 38 to permit vertical movement thereof is accomplished by means of a plurality of pins 42 mounted upon the bottom wall of the body 11 and extended freely into openings 43 formed in the pin bar 38. Certain of the pins 42 are provided with collars 44 for limiting downward movement of the pin bar 38 to positions in which the pins 39 will be completely disengaged from the openings 43 and in which their top ends will be disposed beneath the bottom of the slot 14. Other of the pins 42 have expansion springs 45 coaxially mounted thereon for urging the pin bar 38 into its normal operative position.

Means is provided for urging the pin bar 38 downwards and is controlled by the solenoid 27 to free the endmost toilet seat cover 24 to be slightly ejected through the slot 14. This means comprises an arm 46 for each of the side arms 31 of the yoke 29. These arms 46 have their bottom ends resting on the top face of the pin bar 38 and have their top ends 47 bent at right angles into the body thereof and extended through a slot 48 formed in the side of the arms 31. Springs 49 are mounted within the slots 48 and operate between the top wall of the slots 48 and the inwardly bent ends 47 of the arms 46 for urging them into an operative position to cause the bottom ends to engage the top face of the pin bar.

When the solenoid 27 is energized and the yoke 29 moves downwards the arms 46 will move therewith to urge the pin bar 38 downwards until its bottom face rests upon the collars 44. Further downward movement of the arms 46 will be arrested and as the yoke 29 continues downwards the springs 49 will be compressed permitting the yoke 29 to move downwards independently of the arms 46. When the pin bar 38 rests on the collars

44 the pins 39 will be withdrawn from the openings 43 and will have their top ends disposed beneath the slot 14, leaving the slot free to permit the endmost seat cover to be slightly projected therethrough.

After the toilet seat cover has been slightly projected therethrough it is adapted to be gripped and pulled for completely extending the same to permit it to be separated from the roll of covers adjacent the next complete line of perforations 25.

In Fig. 16 the operating circuit for controlling the movement of the yoke 29 is illustrated. This circuit includes a portion of the track 50 of the coin control mechanism 17 down which a coin, illustrated by the dot and dash lines 51, is adapted to roll. An electric switch 52 is mounted upon the bottom wall of the track 50 and is adapted to be closed when the coin 51 rolls thereover. A pair of electric leads 53 and 54 extend from the switch 52. The lead 53 is connected with one pole of a source of power and the lead 54 extends to one end of a solenoid 55. A lead 56 extends from the other end of the solenoid 55 and connects with the other pole of the source of power. The solenoid 55 has a core 57 supporting a switch element 58 which is adapted to extend across a pair of contacts 59 when the core 57 is raised by the energizing of the solenoid 55.

A lead 60 extends from one of the contacts 59 and connects with one end of the solenoid 27. A lead 61 extends from the other end of the solenoid 27 and connects with one pole of a source of power. A lead 62 extends from the other pole of the source of power and extends through a time switch 63 to the other contact 59. Thus when the switch member 58 is raised to close the contacts 59, this circuit will be completed and the solenoid 27 will be energized to move its core 28' downwards. The time switch 63 is associated with a mechanism for holding the switch element 58 in its closed position for a predetermined length of time even though the switch 52 opens and the solenoid 55 is de-energized. This means comprises a pivotally mounted latch member 64 which is adapted to engage beneath the switch member 58 in its raised position and which is urged into an operative position by a spring 65. Means is provided for counteracting the action of the spring 65 to pivot the latch member 64 and release the switch element 58 after a predetermined time has elapsed to permit the switch element 58 to move away from the contacts 59. A spring 66 is provided for moving the switch element 58 to its open position.

The means for counter-acting the action of the spring 65 comprises a solenoid 67 having its core 68 pivotally attached to the side of the catch element 64 opposed to the spring 65. A lead 69 extends from one side of the solenoid 67 through the time switch 63 and connects with one pole of a source of power.

A second lead 70 extends from the other side of the solenoid 67 and connects with the other pole of a source of power. These electrical circuits are so arranged that they cause the solenoid 27 to be energized for a sufficient length of time to slightly urge the pin bar 38 downwards to withdraw its pins 39 and to rotate the gear 33 to slightly eject the endmost seat cover 24. After this period of time has elapsed, before the seat cover 24 may be readily pulled from the casing, the solenoid 27 is de-energized causing the yoke 29 to move upwards freeing the pin bar 38 to be urged upwards by the springs 45 and engage the bottom face of the toilet seat cover as the re-

maining portion is pulled from the casing. When the next line of perforations reach an aligned position with the pins 39 the pins will be extended therethrough and prevent further pulling to extend the next toilet seat, but leaving the extended seat free to be separated from the roll of seat covers along the line of perforations through which the pins 39 extend.

Means is provided for causing the seat covers 24 to be slowly pulled through the slot 14 giving the pins 39 ample opportunity to engage the endmost perforations of the line of perforations 25'. This means comprises a brake mechanism 71 mounted on the shaft 32 supporting the roll of toilet seats 21. The brake mechanism is characterized by a brake drum 72 securely mounted upon the shaft 22 and encircled by a brake band 73 having a lug 74 securely mounted upon one wall of the casing by means of screws 75. The ends of the brake band 73 are directed away from the drum 72. A screw 76 is freely passed through one of these ends and threadedly engages an opening in the other of these ends, permitting the ends to be drawn together as the screw 76 is rotated to control the frictional engagement of the brake 73 about the drum 72.

The operation of this device is as follows:

To cause the endmost seat cover 24 to be projected through the slot 14 a coin 51 is passed into the receiving opening of the coin control mechanism 17. The coin 51 will close the switch 52 to energize the solenoid 55 and move the switch element 58 to close the contacts 59 and energize the solenoid 27. The core 28' of the solenoid 27 will move downwards moving the yoke 29 also downwards. This downward movement will cause the pin bar 38 to be instantly moved downwards and will also rotate the feed rollers 25 to slightly eject the leading edge of the endmost toilet seat cover 24. After a certain period of time has elapsed which is sufficient to permit the end of the seat cover 24 to be properly projected from the slot 14, the time switch 63 will operate to permit the switch element 58 to be moved to its open position and de-energize the solenoid 27. This will permit the yoke 29 to also move back to its normal position, freeing the pin bar to cause its pins to engage the bottom face of the slightly ejected toilet seat. The projected end is then pulled and the rate of pulling is restrained by the brake mechanism 71, and as the next line of perforations come into aligned position with the pins 39, the pins will project through the side perforations of this line of perforations, preventing further pulling on the endmost seat cover. However, the endmost seat cover will be free to be torn along the line of perforations to be separated from the roll. To eject the next seat cover another coin must be inserted into the receiving slot 16 and the above process will be repeated.

It is known that in a large percentage of the spread of diseases, such as: all forms of venereal diseases, skin infections, common colds, catarrh, influenza, tuberculosis, erysipelas, dysentery, gastric diseases, zymotic diseases, urogenital diseases, and other diseases the mode of infecting the human body is directly and definitely traceable to public lavatories. The object of this invention is to check this condition and to guard against spread of the above mentioned possible diseases.

This device may be placed in one of many places, with mutual benefit to the owner of the premises where this machine is located, and the user of the device.

It may be installed in: public comfort stations,

lavatories of organizations and institutions, semipublic lavatories, large office buildings, hotels, factories, living quarters of workmen's crews, armies, hospitals, gymnasiums, universities, etc.

5 Furthermore, this invention will eliminate the fear of using public and semipublic comfort stations. This fear is known to all, and if eliminated, such places will be used more frequently by even the most discriminating people.

10 The machine is enclosed so that the paper covers shall not be exposed to the foul odors of the room, and should be hung on the wall, high above the ground and not near the toilet seat proper.

15 The toilet seat covers should be impregnated with a disinfectant, as an additional aid for the protection of the user against possible communicable diseases.

20 While I have illustrated and described the preferred embodiments of my invention, it is to be understood that I do not limit myself to the precise constructions herein disclosed and the right is reserved to all changes and modifications coming within the scope of the invention as defined in the appended claims.

25 Having thus described my invention, what I claim as new, and desire to secure by United States Letters Patent is:

30 1. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and having pins engaging through one line of said perforations, means for moving said pin bar to withdraw its pins from said perforations, means for slightly ejecting the toilet strip when freed of said pins, resilient means urging said pin bar to engage its pins against one side of said toilet seat strip, whereby said toilet seat strip may be pulled out until stopped by said pins engaging the next line of perforations, said means for slightly ejecting the toilet strip comprising a solenoid, a core extending from said solenoid and carrying a yoke, a pair of feed rollers engaging opposite sides of the seat cover to be ejected, downwardly extended arms forming a part of said yoke and one arm being formed with gear teeth, a gear coaxially freely mounted adjacent one of said feed rollers and said toothed arm and engaged thereby, and means for locking said gear to said roller for advancing said feed roller to eject said seat cover when said yoke moves in one direction, and for idling when the yoke moves in the other direction.

35 2. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and having pins engaging through one line of said perforations, means for moving said pin bar to withdraw its pins from said perforations, means for slightly ejecting the toilet strip when freed of said pins, resilient means urging said pin bar to engage its pins against one side of said toilet seat strip, whereby said toilet seat strip may be pulled out until stopped by said pins engaging the next line of perforations, said means for slightly ejecting the toilet strip comprising a solenoid, a core extending from said solenoid and carrying a yoke, a pair of feed rollers engaging opposite sides of the seat

cover to be ejected, downwardly extended arms forming a part of said yoke and one arm being formed with gear teeth, a gear coaxially freely mounted adjacent one of said feed rollers and said toothed arm and engaged thereby, and means for locking said gear to said roller for advancing said feed roller to eject said seat cover when said yoke moves in one direction, and for idling when the yoke moves in the other direction, said latter means comprising a ratchet wheel fixedly mounted with relation to said feed roller on one side of said gear, and a spring pressed pawl mounted upon said gear and engageable with the teeth of said ratchet wheel.

3. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and having pins engaging through one line of said perforations, means for moving said pin bar to withdraw its pins from said perforations, means for slightly ejecting the toilet strip when freed of said pins, resilient means urging said pin bar to engage its pins against one side of said toilet seat strip, whereby said toilet seat strip may be pulled out until stopped by said pins engaging the next line of perforations, said means for slightly ejecting the toilet strip comprising a solenoid, a core extending from said solenoid and carrying a yoke, a pair of feed rollers engaging opposite sides of the seat cover to be ejected, downwardly extended arms forming a part of said yoke and one arm being formed with gear teeth, a gear coaxially freely mounted adjacent one of said feed rollers and said toothed arm and engaged thereby, and means for locking said gear to said roller for advancing said feed roller to eject said seat cover when said yoke moves in one direction, and for idling when the yoke moves in the other direction, said means for moving said pin bar comprising arms mounted on the side arms of said yoke and engaging the top face of said pin bar, and means for resiliently mounting said arms upon said side arms permitting movement of said yoke independently of said arms after said pin bar is completely moved.

4. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and having pins engaging through one line of said perforations, means for moving said pin bar to withdraw its pins from said perforations, means for slightly ejecting the toilet strip when freed of said pins, resilient means urging said pin bar to engage its pins against one side of said toilet seat strip, whereby said toilet seat strip may be pulled out until stopped by said pins engaging the next line of perforations, said means for slightly ejecting the toilet strip comprising a solenoid, a core extending from said solenoid and carrying a yoke, a pair of feed rollers engaging opposite sides of the seat cover to be ejected, downwardly extended arms forming a part of said yoke and one arm being formed with gear teeth, a gear coaxially freely mounted adjacent one of said feed rollers and said toothed arm and engaged thereby, and means for locking said gear to said roller for advancing said feed roller to eject said seat cover when said yoke moves in one direction, and for idling when the

yoke moves in the other direction, said means for moving said pin bar comprising arms mounted on the side arms of said yoke and engaging the top face of said pin bar, and means for resiliently mounting said arms upon said side arms permitting movement of said yoke independently of said arms after said pin bar is completely moved, said latter means comprising springs mounted within slots formed in said side arms and said arms having their top ends extended into said slots and engaged beneath said springs.

5. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and having pins engaging through one line of said perforations, means for moving said pin bar to withdraw its pins from said perforations, means for slightly ejecting the toilet strip when freed of said pins, resilient means urging said pin bar to engage its pins against one side of said toilet seat strip, whereby said toilet seat strip may be pulled out until stopped by said pins engaging the next line of perforations, said pin bar being mounted adjacent the bottom of said discharge slot and having its pins extended upwards, and a bar mounted adjacent the top of said discharge slot and formed with openings into which said pins are extended.

6. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and having pins engaging through one line of said perforations, means for moving said pin bar to withdraw its pins from said perforations, means for slightly ejecting the toilet strip when freed of said pins, resilient means urging said pin bar to engage its pins against one side of said toilet seat strip, whereby said toilet seat strip may be pulled out until stopped by said pins engaging the next line of perforations, pins extending from the bottom wall of said casing and freely projected into openings formed in said pin bar, and certain of said pins being provided with coaxial expansion springs for urging said bar upwards and comprising said resilient means, and other of said pins being provided with collars for limiting downward movement of said pin bar.

7. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and having pins engaging through one line of said perforations, means for moving said pin bar to withdraw its pins from said perforations, means for slightly ejecting the toilet strip when freed of said pins, resilient means urging said pin bar to engage its pins against one side of said toilet seat strip, whereby said toilet seat strip may be pulled out until stopped by said pins engaging the next line of perforations, and means for restraining the pulling of said endmost seat cover to insure the engagement of said pins with said perforations.

8. A vending machine for sanitary individual toilet seat covers, comprising a casing having a discharge slot for the toilet seat covers, a con-

tinuous strip of individual toilet seat covers which are separated from each other by lines of perforations, a pin bar extended along one side of said discharge slot and having pins engaging through one line of said perforations, means for moving said pin bar to withdraw its pins from said perforations, means for slightly ejecting the toilet strip when freed of said pins, resilient means urging said pin bar to engage its pins against one side of said toilet seat strip, whereby said toilet seat strip may be pulled out until stopped by said pins engaging the next line of perforations, and means for restraining the pulling of said endmost seat cover to insure the engagement of said pins with said perforations, said continuous strip of individual seat covers being fixedly mounted upon a rotative shaft, and said latter means comprising a brake arranged in connection with said shaft.

9. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and engaging through one line of said perforations, means for moving said pin bar to withdraw its pins from said perforations, means for ejecting said toilet seat when freed from said pins, resilient means urging said pin bar to engage its pins against one side of said toilet seat strip, whereby said toilet seat may be ejected until stopped by said pins engaging the next line of perforations, said means for moving said pin bar, comprising a slidably mounted rod having its bottom end resting upon the top face of said pin bar, said rod having its free top end projected into a coin chute to be engaged and depressed by a coin to lower said pin bar, and means for holding said coin in position over the top end of said rod until said seat cover has been moved to disalign said perforations and said pins.

10. A vending machine for sanitary individual toilet seat covers, comprising a casing having a discharge slot for the toilet seat covers, a continuous strip of individual toilet seat covers which are separated from each other by lines of perforations, a pin bar extended along the side of said discharge slot and engaging through one line of said perforations, means for moving

said pin bar to withdraw its pins from said perforations, means for ejecting said toilet seat when freed from said pins, resilient means urging said pin bar to engage its pins against one side of said toilet seat strip, whereby said toilet seat may be ejected until stopped by said pins engaging the next line of perforations, said means for moving said pin bar, comprising a slidably mounted rod having its bottom end resting upon the top face of said pin bar, said rod having its free top end projected into a coin chute to be engaged and depressed by a coin to lower said pin bar, and means for holding said coin in position over the top end of said rod until said seat cover has been moved to disalign said perforations and said pins, comprising a second slidably mounted rod having its free top end projected into said coin chute to be engaged by the leading edge of said coin.

11. A vending machine for sanitary individual toilet seat covers, comprising a casing having a discharge slot for the toilet seat covers, a continuous strip of individual toilet seat covers which are separated from each other by lines of perforations, a pin bar extended along one side of said discharge slot and engaging through one line of said perforations, means for moving said pin bar to withdraw its pins from said perforations, means for ejecting said toilet seat when freed from said pins, resilient means urging said pin bar to engage its pins against one side of said toilet seat strip, whereby said toilet seat may be ejected until stopped by said pins engaging the next line of perforations, said means for moving said pin bar, comprising a slidably mounted rod having its bottom end resting upon the top face of said pin bar, said rod having its free top end projected into a coin chute to be engaged and depressed by a coin to lower said pin bar, and means for holding said coin in position over the top end of said rod until said seat cover has been moved to disalign said perforations and said pins, comprising a second slidably mounted rod having its free top end projected into said coin chute to be engaged by the leading edge of said coin, and means for permitting said second rod to move downwards to free said coin to roll off the top end of said first rod freeing said first rod and pin bar to move upwards.
